UNITED STATES PATENT OFFICE.

DAVID FARQUHAR, OF LINCOLN, MASSACHUSETTS.

BOOK.

1,243,394.

Specification of Letters Patent. Patented Oct. 16, 1917.

Application filed October 18, 1915. Serial No. 56,379.

To all whom it may concern:

Be it known that I, DAVID FARQUHAR, a citizen of the United States, residing in Lincoln, in the county of Middlesex and State 5 of Massachusetts, have invented an Improvement in Books, of which the following description, in connection with the accompanying drawings, is a specification, like characters on the drawings representing like 10 parts.

This invention relates to books and has for its object to produce a superior book at a minimum expense, and especially renewed books whose leaves are composed of paper 15 of inferior quality, such, for instance, as are found in old books used in public libraries.

When a book embodying this invention is made from old books, the leaves of the latter are first trimmed off and stacked up or 20 alined so that the back edges of the leaves are square or in the same plane. A series of holes are then punched through the leaves near the back edges thereof, which may be effected by a gang of needles in a suitable 25 machine, said needles being uniformly spaced apart, preferably about one-half inch. The needles penetrate the leaves simultaneously, and each needle forms a hole in each 30 of the superimposed leaves, so that the holes formed in all the leaves by each needle register with one another and form a column of holes, and the columns of holes formed in the leaves are located a uniform distance from the back edge of the leaves and from 35 each other. The leaves are then sewed together by stitches formed from a continuous length of thread, and said stitches are made as will be described, so that preferably straight outside stitches are formed across 40 the back of the leaves at the opposite ends thereof and inclined outside stitches are formed between the endmost stitches, while straight stitches are formed in the columns 45 of holes in the leaves, for a purpose as will be described.

In starting to sew the leaves, a sufficient length of thread is preferably left on one side of the stack of leaves for the purpose of sewing an end cover or fly-leaf to one 50 side of the book, and in finishing the sewing a like length of thread is used to sew an end cover or fly leaf on the opposite side of the book. Those end portions of thread may and preferably will be knotted or 55 surely tied to the straight end stitches, so that the end covers or fly-leaves are hinged

to the stitches employed to sew the leaves of the book together.

The outside stitches and particularly the inclined stitches are preferably left slack or 60 somewhat slack, so as to permit the back of the book to be rounded when the cover is applied thereto, which is done in the manner now commonly practised, and also for the purpose of affording sufficient freedom 65 between the leaves, to allow the book to be opened up freely or substantially flat at any part without placing strain upon the paper leaves or upon the thread itself, and when the book is opened up the individual leaves 70 can be turned freely on the stitches as guides without tearing the leaves or placing strain upon the same.

The stitches pass through all of the leaves of the book within the back edge of said 75 leaves, and also on the outside of said leaves, and the latter enable reinforcing tape strips usually employed on the back of the book to be dispensed with.

The particular features of this invention 80 will be pointed out in the claims at the end of this specification.

Figure 1 is a view of a book embodying 85 this invention.

Fig. 2, a view with the book shown in 85 Fig. 1 opened into a substantially flat position.

Fig. 3, a plan of the leaves of the book shown in Figs. 1 and 2 provided with the 90 needle holes and stacked in position ready for stitching.

Fig. 4, an elevation of the stack of leaves shown in Fig. 3.

Figs. 5 and 6, enlarged views of the leaves to illustrate the sewing. 95

Fig. 7, a detail in section to illustrate the straight stitches, and

Fig. 8, a detail in plan of the cover leaf opened.

Referring to the drawing, *a* represents a 100 book embodying the invention and *b* the leaves thereof.

The leaves *b* may be new or fresh, or they may be those of an old book, and inasmuch as the invention is especially serviceable for renewing old books whose leaves are of the poorer quality of paper, such, for instance, as old books used in public libraries and subject to constant use and wear, I will describe in detail the method of renewing old books. 110

The leaves *b* of the old book are trimmed

to the same size, and then placed in a suitable machine (not shown), but which is provided with a gang of needles spaced apart, preferably about one-half inch.

- 5 The needles are forced through the stack of leaves *b* to form a series of holes *c* (see Figs. 3 and 4) which are located near the back edge of the leaves, or what may be termed the back of the book.
- 10 After the holes *c* have been formed, the stack of leaves are then sewed together, which is done by hand as herein illustrated and which may be accomplished in the following manner:
- 15 The operator assembles all the leaves which are to be sewed, so that the holes in the leaves are alined or register to form a series or plurality of columns of holes, as represented by dotted lines in Fig. 4.

- 20 It may be preferred to insert a needle or other device in one of the endmost columns of holes to preserve the alinement, when the sewing is begun.

The operator then starts at the other end 25 of the stack of leaves, to wit:—the left hand end, viewing Figs. 4 and 5, by passing a threaded needle down through the left hand column 10 of holes in Figs. 4 and 5, leaving a length of thread 12 above the stack, 30 which is greater than the length of the leaves, for a purpose as will be described. A straight stitch 13 is thus formed in the column 10 of holes (see Fig. 7).

The threaded needle is then carried up 35 and again passed down through the column 10 of holes, and the slack in the thread is taken up so as to form a straight stitch 14 outside of and across the back of the leaves *b* and a straight stitch 15 in the column 10 of holes, so that the endmost column 10 of holes has in it two straight stitches 13, 15.

The operator then carries the thread up 45 across the back of the leaves and passes it down through the next column of holes marked 16 in Figs. 4 and 5, and then up across the back and down through the next column of holes marked 17, and so on, until the endmost column of holes marked 18 is reached, thereby forming on the outside of 50 the leaves *b* a series of inclined stitches 19. When the operator arrives at this last column 18 of holes, the alining needle above referred to is removed, and the thread is passed down through the column 18 to form 55 the straight stitch 20 and then up across the back of the leaves to form the straight outside stitch 21 and then down through the column 18 of holes, again to form a second straight stitch 22. The operator then un- 60 threads the needle and leaves a length 23 of thread, which is greater than the length of the leaves, for a purpose as will be described. It will be understood that the thread is drawn upon sufficiently to bring 65 the stitches on the outside of the leaves sub-

stantially close to the same and yet leave them more or less slack, for a purpose as will be described.

The surplus lengths 12, 23 of threads are then employed for sewing the cover or fly 70 leaves 24, 25, to the book (see Fig. 6), and this may be done as follows: Referring to Fig. 5, the surplus length 12 of thread is threaded through a needle and is preferably first tied or knotted to the straight threads 75 13, 15, on top of the leaves, and the surplus length 12 is then passed through the cloth or other strips 26 (see Fig. 8), which binds together two fly leaves or cover leaves 24, and then under one or more of the inclined 80 threads 19 up through the cloth strip 26 and so on, until the straight end stitches 20, 21, are reached, whereupon the thread 12 is tied or knotted to these straight stitches.

The book is reversed, and the cover or fly 85 leaves 25 are sewed in a like manner, to the end stitches 20, 21, 13, 15, and inclined stitches 19 by the surplus length 23, which is tied or knotted to the straight end stitches.

In this manner, the cover or end or fly 90 leaves 24, 25 are firmly yet flexibly secured to the book, and by reason of the knots, they are capable of turning as on a hinge.

A superior book is thus produced in a minimum time and at a minimum cost over 95 the method now commonly practised in renewing old books, for the reason that the outside stitches and particularly the inclined stitches are left more or less slack, so that when the cover 30 of the book is applied thereto by the method of binding now commonly practised, the back of the book may be rounded in the proper or desired manner now commonly practised in binding books, and at the same time afford sufficient 100 freedom between the leaves to allow the book to be opened up freely at any part, as represented in Fig. 2, without placing strain upon the paper leaves or upon the stitches, which allows a stronger thread to be used 105 and a stronger book to be produced, as the outside threads reinforce the book at its back.

Furthermore, it will be noticed that the straight stitches 15, which pass through the 110 leaves are all at the same or uniform distance from the back edges of all of the leaves, and in the completed book are substantially parallel and extend transversely thereof, and consequently each leaf in the 115 book can be turned back and opened up to the same point or position, as each leaf can be turned freely on the straight stitches 15 as guides, and when the book is closed, the threads return to their proper position and 120 still hold their original tension.

Claims:

1. As a new article of manufacture, a book having all of its leaves united together and to cover leaves by a single length of 130

thread forming straight stitches within the back edge of the leaves and inclined stitches outside of the back edge of said leaves and stitches extended lengthwise of the uppermost and lowermost leaves of the book, the latter stitches uniting said cover leaves with the leaves of the book.

2. As a new article of manufacture, a book having its leaves united by a plurality

of straight stitches extended through the leaves transversely of the book and by inclined stitches located outside of said leaves and extended across the back edges of the same and connecting said straight stitches, and cover leaves hinged to said stitches.

15

In testimony whereof, I have signed my name to this specification.

DAVID FARQUHAR.
